CONTROL SYSTEM

William F. Eames, Edgewood, Pa., assignor to
Westinghouse Electric & Manufacturing Com-
pany, a corporation of Pennsylvania

Application October 11, 1929, Serial No. 398,942

8 Claims. (Cl. 187—29)

My invention relates to signalling systems and more particularly to signalling systems employed in elevator systems.

One object of my invention is to provide a signalling system in which a minimum amount of wiring is required for connecting the various pieces of apparatus embodied in the system.

Another object of my invention is to provide a signalling system having a floor selector with a very small number of contact strips and segments.

A further object of my invention is to provide for reducing the number of relays required in constructing an elevator signalling system.

Another object of my invention is to provide for maintaining a push button in its depressed condition until an elevator car has been conditioned to answer the signal set up by the depressed button so as to indicate to passengers that the button has been pressed and that a "stop" call is registered.

Another object of my invention is to provide for releasing a depressed button as soon as some step has been taken to answer the signal registered on that button.

Another object of my invention is to provide a fully selective elevator signalling system, that is, a system in which a registered call is cancelled the instant that a car starts to answer the call, thereby preventing a following car from receiving the same signal.

A further object of my invention is to provide a means for restoring or resetting an operated push button that shall be simple and efficient in operation and capable of being readily and economically manufactured, installed and maintained.

It is also an object of my invention to provide for causing a car to be decelerated from an express speed to its normal operating speed when it approaches at express speed a landing for which a signal stop exists so that it may receive the stop signal while running at a speed that will permit it to be stopped at that landing and to also provide for causing the car to resume its express speed after the stop has been made.

Other objects of the invention will, in part, be obvious and will, in part, appear hereinafter.

For a fuller understanding of the invention reference may be had to the following description taken in connection with the accompanying drawings in which

Figures 1 and 2 constitute a diagrammatic representation of the control circuits and apparatus

embodimenting my invention as applied to an elevator system.

Fig. 3 is a diagrammatic representation of the windings of one of the push buttons holding and restoring magnets.

The drawings illustrate an elevator car C as suitably suspended upon a cable Ca which passes over a hoisting drum D to a suitable counter-weight Cw. The hoisting drum D is directly coupled to the armature EM' of an elevator motor EM, the field winding EMF of which is connected, for constant voltage energization, to a source of power designated as the supply conductors L1 and L2.

A variable voltage system of control may be provided for operating the hoisting motor EM wherein the armature EM' of the hoisting motor is connected in loop circuit with the armature G' of a generator G. The generator G is provided with a separately excited field winding GF and a cumulative series field winding GSF.

The armature G' of the generator G is suitably driven by means of a driving motor M illustrated as being of the shunt wound type having its armature M' and its field winding MF connected in shunt relation to the supply conductors L1 and L2.

The direction and speed of the hoisting motor EM may be suitably controlled by controlling the direction and value of the excitation current that is supplied to the separately excited field winding GF of the generator G.

The direction of the excitation current for the field winding GF may be suitably controlled by means of an up-direction switch 1 and a down-direction switch 2, while the value of the current supply to the field winding may be controlled by means of an intermediate speed relay 3, a normal or high-speed relay 4, and an express-speed relay 5.

The operation of the up-direction and the down-direction switches 1 and 2, as well as the intermediate speed relay 3 and the normal or high-speed relay 4 may be controlled by means of a car switch CS that is mounted upon the car C in position to be actuated by an attendant thereon.

An express-speed switch 9 is provided for controlling the express-speed relay 5. The switch 9 may be disposed at any suitable point where the "dispatcher" in charge of the elevator may close the switch to speed up the operation of the elevator at any time desired. For instance, if the high speed, that is, the normal working speed of the car is, say 700 feet per minute the

"dispatcher" may cause it to operate at an express-speed of say 800 feet per minute.

A relay 6 is connected with the elevator signaling system in such manner that it will operate to deenergize the express-speed relay 5 to decelerate the car from express speed to its high speed, that is, its normal working speed when it nears a registered call for a stop.

A voltage or counter electromotive force relay 7 is connected across the loop circuit of the motor EM and provided with contact members that open or close gaps in the energizing circuits for the high-speed relay 4 and the express-speed relay 5, thereby delaying the energization of these relays until the generator reaches a predetermined speed.

The use of the relay 7 permits the automatic selection of a one-floor run or a two-floor run, dependent upon the time during which the car switch is held in full speed position. It is undesirable to force the attendant to carefully operate the car switch, when making a one-floor run, to such a position as it will engage only the intermediate speed contact members, it being preferable that he be permitted to throw the car switch to its extreme position regardless of the distance the car is to travel. Without the delay imposed by the relay 7, movement of the car switch to its high speed position would cause the car to accelerate to its highest speed from which it would be impossible to decelerate to stop at the next adjacent floor. However, by employing the relay as described, the attendant may move the car switch to its full speed position and then immediately return it to its neutral position, without the possibility of energizing the high speed relay 4, and the car will accelerate only to its intermediate speed and then decelerate to the stop at the next floor.

Inasmuch as the relay 7 also prevents the energization of the express speed relay 5 until the generator reaches a predetermined speed, it also prevents too much current from being applied suddenly to the generator and a resulting unpleasant acceleration, if the car switch is moved to full speed position at a time when the express-speed switch is closed.

A control system of any suitable type may be employed for automatically stopping the car C level with the floors past which it moves, though I have illustrated the control system as of the automatic inductor landing type such as disclosed in the copending application of E. M. Bouton, Serial No. 731,291, filed August 14, 1924, and assigned to the Westinghouse Electric & Manufacturing Company.

The inductor landing system includes an up high speed inductor relay HU, an up intermediate speed inductor relay SU and a stopping inductor relay S for causing the car to be automatically decelerated from its high and intermediate speeds, respectively, and brought to a stop at an exact landing with a floor when the car is travelling upwardly. Similarly, a down high speed inductor relay HD, a down intermediate speed inductor relay SD and the stopping inductor relay S will cause the car to slow down and stop at the floors when it is travelling downwardly.

It is assumed that each of the floors past which the car moves will be provided with a set of inductor plates that will cooperate with the inductor relays as the car approaches predetermined points in advance of the floor at which a stop is to be made, to effect the operation of the relays.

The inductor plates associated with any one

floor are illustrated as comprising an up high speed inductor plate HU', an up intermediate speed inductor plate SU', and a stopping inductor plate S' for successively operating the up inductor relays HU, SU and S as the car makes an up stop. When the car is travelling downwardly, a high speed inductor plate HD', an intermediate speed inductor plate SD' and the stopping inductor plate S' will successively operate the inductors HD, SD and S, respectively, as the car approaches a down stop.

In adapting my system to elevator installations of the high speed type in which the slow down distance of the car C is greater than the distance between two adjacent floors, I have provided the car C' with two signal-giving devices, preferably electric lamps, a red lamp RL for indicating that a stop is to be made at a floor more than one floor away and a green lamp GL for indicating, while the car is standing at a floor, that a stop is to be made at the next floor.

It will be noted that each lamp is provided with two filaments *a* and *b* respectively in order that it may be readily connected in the signal circuits for the elevator in such manner that push buttons operated in any one car will not disturb the signals for any other car. The "*a*" filaments are arranged to operate in response to floor push buttons and the "*b*" filaments to the car push buttons. It will be understood, however, that separate lamps may be used in place of the two filament lamps shown. The circuits for the red lamp RL are connected to the signal system of the elevator, so that this lamp will be operated when the car is running at high speed.

The circuits for the green lamp GL are connected to the signalling system of the elevator through normally closed contact members on the up and down switches 1 and 2 in such manner that the lamp GL may be energized only while the car is standing at a floor.

In order that waiting passengers at a floor landing may register or "set up" signals for stops to be made at that landing which will cause the signal lamps in the car to give the attendant on the car a stop signal as the car approaches that landing, a pair of signal-registering push buttons is mounted at each of the landings intermediate the terminal floors, one for up travel and one for down travel. This system is illustrated as adapted for an elevator serving nine floors. The "up" and "down" buttons for the second floor are respectively designated as 2U and 2D while those for the third and eighth floors are designated as 3U and 3D, and 8U and 8D.

Push buttons C2, C3 and C8 (one for each floor) are mounted on the car C to be operated by the car attendant when he desires to set the signal-giving devices to indicate stops to permit passengers to get off at corresponding floors.

For the purpose of signalling a passenger waiting at a floor that a car is approaching in the direction in which he desires to go and will make a stop at his landing, the car is electrically connected to indicating devices, preferably electric lamps, which are mounted outside of the elevator shaft at the floor landings. Each of the top and bottom floors is provided with a single lamp or floor lantern, while each of the intermediate floors is provided with a pair of lanterns, one serving to indicate that the car is approaching in a downward direction and the other in an upward direction. The floor lanterns are designated as L1, L2D, L2U, L3D, L3U, L8D, L8U and L9. 75

In order that the various circuits for the push buttons, signal lamps and floor lanterns may be connected in accordance with the position of the car, the car is provided with a floor selector FS. 5 The floor selector may be located at any suitable point, for example, in the pent house or the elevator shaft and, as illustrated, is similar to those usually employed in elevator signalling systems.

As shown, the selector FS is provided with a 10 set of "up" contact segments and a set of "down" contact segments that are disposed to be engaged by cooperating brushes 10 to 27, inclusive, mounted upon and insulated from a movable arm MA. The movable arm MA is operated in accordance 15 with the movements of the car by means of a screw S that is driven by some part of the operating mechanism of the car which the selector serves.

Usually the frictional engagement between the 20 arm MA and its operating screw S will cause the arm to bear upon the "up" contact segments when the car is travelling upwardly and upon the "down" contact segments when the car is travelling downwardly. However, in the present system, it is desirable to have the movable arm tilted 25 to the opposite side as soon as it reaches the limit of its up or down travel. Therefore, the selector is provided with a pair of electro-magnets 30 and 31 that may be energized to cause the arm MA to tilt in the proper direction upon reaching the end of its travel.

The electro-magnets 30 and 31 may be energized 30 to tilt the movable arm MA when the car reaches the limit of its up or down travel by having their coils connected in circuit with and controlled by an "up" selector relay 32 and a "down" selector relay 33 which, in turn, are controlled by a pair of limit switches 34 and 35.

The group of "up" contact segments under the 40 brushes 10, 11 and 12 control the lighting of the floor lanterns to indicate to waiting passengers that the car will stop for them.

The group of "up" contact segments under the brushes 13, 14 and 15 connect the floor buttons and the group of "up" contact segments under the brushes 16, 17 and 18 connect the car buttons with the signal devices in the car.

As shown, the brushes 10, 11 and 12 for the 50 "up" floor lantern segments are so disposed on the arm MA that the high speed brush 10 will engage the floor lantern segment for a floor when the car is two floors away from that floor, the intermediate speed brush 11 will engage the segment when the car is one floor away, and the standing brush 12 will be in engagement with the segment when the car is standing, thus providing means whereby an energized segment will keep a floor lantern lighted while a car decelerates from high speed to a stop at a floor and remains standing at that floor.

The express brush 13 for the "up" floor button segments is so disposed on the arm MA that it will engage the floor button segment for a floor when the car is approximately three floors away from that floor. The express brush 13 is connected in the circuit for the coil of the controlling relay 6. Therefore, when the express brush 13 comes into engagement with a contact segment that has been energized by the registration of a stop call, it will energize the relay 6 to open the circuit for the express relay 5.

Thus, if the car approaches a registered call at express speed, the express brush 13 will come into engagement with the energized segment when the

car is three floors away from the floor for which the call exists and will thereby cause the car to decelerate from its express speed to its normal high speed so that it may pick up the registered call while it is running at such a speed that it can be stopped at the floor for which the stop call exists.

The brushes 14 and 15 for the "up" floor button segments are disposed on the arm MA in such manner that the high speed brush 14 will engage 10 the floor button segment for a floor when the car is approximately two floors away from that floor, and the standing brush 15 will be in engagement with the segment when the car is one floor away, thus providing separate circuits for operating the high speed signal and the low speed or standing signal devices in the car.

The express brush 16, the high speed brush 17 and the standing brush 18 for the "up" car button segments are disposed on the arm MA in 20 a manner similar to the brushes 13, 14 and 15 for decelerating the car when a car button has been pressed to energize a car button segment for a stop.

The "down" side of the selector comprises a 25 duplicate of the "up" contact segments and brushes, except for a reversal of their order and position.

For the purpose of simplifying the drawings, only one elevator car has been illustrated, but 30 any number of cars may be included in the signal system shown by connecting their signal circuits to the floor buttons through the conductors marked with the legend "to other cars."

My invention may be understood best from an 35 assumed operation of the apparatus represented in the drawings.

Assuming that the car C is standing at the first floor landing and that a passenger waiting at the second floor presses the "up" button 2U, 40 then the green lamp GL in the car will be lighted to indicate to the car attendant that an up stop is to be made at the second floor. At the same time, a circuit will be partially completed for lighting the "up" floor lantern at the second 45 floor when the car approaches and prepares to stop at that floor.

The operation of the push button 2U closes a self-holding circuit for itself that extends from the supply conductor L1 through conductor 50 40, the contact members of button 2U, holding coil 41 and conductor 42 to supply conductor L2. The holding coil 41 will maintain the push button 2U in a closed position, thus the condition of the button will indicate to the waiting 55 passenger that the "stop" signal has been registered, until the car attendant centers the car switch CS to make a stop at the second floor.

Inasmuch as the car is standing at the floor below that floor at which the call exists, the 60 pressing of the button 2U will complete a circuit for lighting the green lamp GL in the car, which circuit extends from supply conductor L1 through conductor 40, the contact members of push button 2U conductor 43, restoring coil 44, 65 conductor 45, the contact segment 46, brush 15, conductors 47 and 48, the contact members d of up-direction switch 1, conductor 49, the contact members d of down-direction switch 2, conductor 50, the filament a of green lamp GL and conductor 51 to supply conductor L2. The illumination of the green lamp GL will indicate to the attendant on the car C that a passenger is waiting at the second floor who desires to travel upwardly.

The car is assumed to normally operate at such high speeds that, in order to stop at a floor, the attendant must center the car switch CS when the car is at a distance from that floor greater than the distance between two adjacent floors. That is, the car switch CS must be centered before the car arrives level with the floor preceding the one at which a stop is to be made. On the other hand, when the car is standing at a floor and receives a signal to stop at the next floor, the attendant should operate the car switch CS to make the one floor run at a speed much lower than the usual high speed.

Therefore, under our assumed condition of operation, the attendant on the car C will start the car from the first floor by operating the switch CS in a clockwise direction to allow the car to travel only at a low speed. The movement of the car switch CS completes a circuit for energizing the up-direction switch 1 to start the car upwardly, which circuit extends from supply conductor L1 through conductors 54, 55, 56 and 57, the normally closed contact members of stopping inductor relay S, conductors 58 and 59, the coil of up-direction switch 1, conductor 60, the contact members 61, 62 and 63 of car switch CS and conductor 64 to supply conductor L2.

The closing of the contact members *a* on up-direction switch 1 completes a self-holding circuit for that switch, which extends from supply conductor L1 to the coil of up-direction switch 1, as just described and then through conductor 66, contact members of up-direction switch 1 and conductors 67 and 68 to supply conductor L2.

The closing of the contact members *b* and *c* on the up-direction switch 1 energizes the field winding GF of the generator G with current in one direction by way of a circuit that extends from supply conductor L1 through conductors 70 and 71, the contact members *b* of up-direction switch 1, conductor 72, the field winding GF, conductors 73 and 74, the contact members *c* of up-direction switch 1, conductors 75 and 76, resistor sections R1, R2 and R3 and conductor 77 to supply conductor L2.

The energization of the field winding GF causes the generator G to supply current in one direction to the hoisting motor EM and the car starts upwardly.

The opening of the contact members *d* on the up-direction switch 1 opens the circuit for the signal lamp GL in the car and thereby extinguishes it.

As the attendant continues the movement of the car switch CS in a clockwise direction, a circuit is completed for energizing the intermediate speed relay 3 for causing the car to operate at its intermediate speed, which circuit extends from supply conductor L1 through conductors 54 and 80, the normally closed contact members of inductor relay SD, conductor 81, the normally closed contact members of inductor relay SU, conductor 82, the coil of relay 3, conductors 83 and 84, the contact members 85, 62 and 63 of switch CS and conductor 64 to supply conductor L2.

The closing of the contact members *a* on the intermediate speed relay 3 completes a self-holding circuit for that relay, extending from supply conductor L1 to the coil of relay 3, as just described and thence through conductor 83, the contact members *a* of relay 3 and conductors 86 and 87 to supply conductor L2.

The closing of the contact members *b* on the intermediate speed relay 3 shunts the resistor

section R3 from the circuit previously traced for the field winding GF to thereby cause the car to travel at a higher speed.

However, inasmuch as the attendant has received the signal to stop at the second floor, he will immediately center his car switch CS, after starting the car, to complete a circuit to energize the slow down inductor relays for stopping the car at the second floor. While I am describing the starting of the car by the "step-by-step" movements of the car switch for the purpose of detailing the circuits, it is to be understood that in actual practice, the attendant, in making a one-floor run, will throw the car switch CS all the way over momentarily and then immediately re-center it, as set forth in connection with the description of the counter E. M. F. relay 7. The circuit completed for energizing the slow down and stopping inductor relays extends from supply conductor L1 through conductors 54, 55, 56 and 90, the coil of stopping inductor relay S, conductors 91 and 92, in parallel through the coils of inductor relays SU and HU, conductor 93, the contact member *f* of up-direction switch 1, conductors 88, 89, 94 and 95, the contact members 96, 62 and 63 of car switch CS and conductor 64 to supply conductor L2.

The energization of the inductor relays HU, SU and S by the centering of the car switch causes the inductor relays to be actuated to open their contact members as they pass the inductor plates SU' and S', and thereby open the circuits for the intermediate speed relay 3 and the up-direction switch 1, thus deenergizing the relay 3 and the up direction switch 1 and bringing the car to a stop at the second floor.

The centering of the car switch CS, in addition to causing the car to stop, also causes the push button 2U to be restored to its normal open position by completing a circuit through the restoring coil 44 on button 2U which extends from supply conductor L1 through conductor 48, the contact members of button 2U, conductor 43, restoring coil 44, conductor 45, the contact segment 46 and the brush 15 on the floor selector, conductor 47, the contact members *c* of high speed relay 4, conductors 98 and 99, the contact members *d* of relay 3, conductor 95, the contact members 96, 62 and 63 of car switch CS and conductors 64 to supply conductor L2.

Inasmuch as the holding coil 41 and the restoring coil 44 on the push button 2U are wound in opposition to each other so as to oppose each other magnetically, when the restoring coil 44 is fully energized, it has sufficient magnetic force to neutralize the magnetic force of the holding coil 41 and thus cause the push button to be released to its normal open position. Therefore, the push button 2U will be released to its open position ready for future operation when full current is supplied to the restoring coil 44 by the completion of the circuit through the centering of the car switch, when the restoring coil was in series with the filament *a* of the green lamp GL during the lighting of that lamp, there was sufficient resistance in the lamp to prevent the restoring coil 44 from being sufficiently energized to overcome the energization of the holding coil 41. Therefore, the push button was not restored to open position at that time.

While the holding coil 41 and the restoring coil may be proportioned with reference to each other in any suitable manner, I prefer to employ a holding coil having a large number of turns of high resistance wire and a restoring coil having a

relatively small number of turns of low resistance wire, as represented in Fig. 3, in order to provide as economical a construction as possible. Such a construction will operate without any undue heating in the restoring coil because it is energized for only an instant and is never in continuous operation as is the holding coil.

The centering of the car switch CS to bring the car to a stop at the second floor also lights the floor lantern L2U at the second floor to indicate that the car will stop at that floor, by completing a circuit that extends from supply conductor L1 through conductors 54 and 55, lamp L2U, conductor 100, contact segment 101 and brush 11 on floor selector FS, conductor 102, the normally closed contact members g on relay 4, conductors 103 and 99, the contact members d on intermediate speed relay 3, conductor 95, the contact members 96, 62 and 63 on car switch CS and conductor 64 to supply conductor L2.

As the car C moves into and stops at the second floor, the arm A on the floor selector moves to such position that the standing brush 12 is disposed on the contact segment 101 and, therefore, the circuit for lighting the floor lamp L2U is transferred from the low speed brush 11 to the standing brush 12, which circuit now extends from supply conductor L1 through conductors 54 and 55, lamp L2U, conductor 100, contact segment 101, brush 12, conductor 105, the normally closed contact members e of intermediate speed relay 3, conductor 95, the contact members 96, 62 and 63 of car switch CS and conductor 64 to supply conductor L2.

Thus, the arrangement of the intermediate speed brush 11 and the standing brush 12 causes the floor lantern L2U to be lighted when the car C is conditioned to stop at the second floor and to thereafter remain lighted while the car slows down and while it stops at the second floor. The floor lantern will be extinguished when the contact members 62 and 96 on the car switch CS are separated by the movement of the switch to start the car.

Assuming now that the waiting passenger at the second floor has been taken on and that the attendant starts the car upwardly by moving the car switch CS in a clockwise direction to engage the contact members 61 and 85 on the car switch, then the up-direction switch 1 and the intermediate speed relay 3 will be energized for operating the car at intermediate speed, as previously described.

Inasmuch as the car attendant has no "stop" call for the next floor, he will cause the car to travel at high speed, by moving the car switch CS in a clockwise direction to a further position in engagement with car switch contact member 106, thereby energizing the high speed relay 4 to operate the car at high speed, by way of a circuit which extends from supply conductor L1 through conductors 54, 80 and 107, the normally closed contact members of inductor relay HD, conductor 108, the normally closed contact members of inductor relay HU, conductor 109, the coil of relay 4, conductor 110, the contact members a of counter E. M. F. relay 7, conductor 111, the contact members 106, 62 and 64 of car switch CS and conductor 64 to supply conductor L2.

The closing of the contact members a on the high speed relay 4 completes a holding circuit for that relay extending from supply conductor L1 to the coil of relay 4, as just described, and thence through conductor 112, the contact mem-

bers a of relay 4 and conductors 113, 86 and 87 to supply conductor L2.

The closing of the contact members b on the relay 4 serves to shunt the resistor section R2 from the circuit previously traced for the field winding GF to thereby cause the car to travel at high speed.

Assuming now that the "dispatcher" in charge of the elevator system closes the express speed switch 9 to speed up the operation of the car C so that it will return to the terminal as soon as possible, then the express relay 5 will be energized to operate the car at its express speed by way of a circuit that extends from supply conductor L1 through conductor 54, the dispatching switch 9, conductor 115, the coil of express relay 5, conductor 116, the contact members a of express controlling relay 6, conductor 117 contact members b on C. E. M. F. relay 7 and conductor 87 to supply conductor L2.

The closing of the contact members on the express relay 5 serves to shunt the resistor section R1 from the circuit previously traced for the field winding GF, thereby allowing full line voltage to be supplied to the winding GF to cause the car to travel at full express speed.

Assuming also that a passenger waiting at the eighth floor landing pressed the up button 8U as the car C left the first floor to answer the second floor call and thereby registered a stop call for the eighth floor; then the pressing of the button 8U energized the holding coil 119 for maintaining the button 8U in a pressed condition by way of a circuit that extends from supply conductor L1 through conductor 120, the contact members of button 8U, holding coil 119 and conductor 42 to conductor L2.

The energization of the holding coil 119 will maintain the button 8U in its pressed condition to indicate to passengers at the eighth floor that it has been operated to register an "up" stop call.

The maintenance of the button 8U in its pressed condition will cause current to be supplied to the contact segment 118 on the floor selector for lighting a signal lamp in the car as it approaches the eighth floor to indicate to the car attendant that a stop is to be made at that floor.

As the car approaches the eighth floor stop at express speed, it will, by reason of the "stop" signal being registered for the eighth floor, be reduced from express speed to high speed because the movable arm MA on the floor selector will cause the express brush 13 to engage the energized contact segment 118, and thereby energize the express control relay 6 by way of a circuit which extends from supply conductor L1 through conductor 120, the contact members of button 8U, conductor 121, the restoring relay 122, conductor 123, contact segment 118, brush 13, conductor 124, the coil 129 of relay 6 and conductors 125 and 77 to supply conductor L2.

The closing of the contact members b on the relay 6 completes a self-holding circuit for that relay which extends from supply conductor L1 through conductors 54, 55, 56 and 57, the normally closed contact members of the inductor relay S, conductors 58 and 126, the contact member b of relay 6, conductor 127 the coil 129 of relay 6 and conductors 125 and 77 to supply conductor L2.

The opening of the normally closed contact members a on the relay 6 deenergizes the express relay 5. The deenergizing of the relay 5 causes its contact members a to open and thus re-insert the resistor section R1 in the circuit for the field

winding GF of the generator to thereby slow down the car to high speed.

As the car continues its approach to the eighth floor, the floor selector arm MA causes the high speed brush 14 to engage the energized contact segment 118 and thereby complete a circuit for lighting the signal lamp RL to indicate to the car attendant that a stop is to be made at the eighth floor, which circuit extends from supply conductor L1 through conductor 120, the contact members of button 8U, conductor 121, restoring coil 122, conductor 123, contact segment 118, brush 14, conductor 130, filament a of lamp RL and conductor 131 to supply conductor L2.

Upon the lighting of the signal lamp RL, the car attendant centers the car switch CS, thereby energizing the inductor relays HU, SU and S as previously described, so that they will be actuated by the inductor plates HU', SU' and S' to cause the car to stop at the eighth floor.

As the car passes the eighth floor inductor plate HU', the energized inductor relay HU will be actuated to open its contact members and thereby open the holding circuit for the high speed relay 4 to automatically slow down the car to intermediate speed.

As the car continues toward the eighth floor level, the energized inductor relay SU passes the eighth floor inductor plate SU' and is actuated to open its contact members to deenergize the intermediate speed relay 3 to automatically bring the car to a still lower speed as it approaches the point at which the power should be cut off.

As the car continues toward the eighth floor level, the energized stopping inductor relay S passes the inductor plate S' and is actuated thereby to open the circuit to the up direction switch 1 for deenergizing the generator winding GF and bringing the car to a stop at the eighth floor.

The opening of the contact members on the stopping inductor relay S also deenergizes the holding circuit for the express control relay 6 thereby restoring that relay to its normal condition in which its contact members a are closed to permit the express relay 5 to be again energized when the "dispatcher" desires to operate the car at express speed.

Upon the centering of the car switch CS for the eighth floor stop, a shunt circuit around the signal lamp RL was completed for fully energizing the restoring coil 122 on the eighth floor push button 8U to overcome the energized holding coil 119 and thus release the button 8U to open position, which circuit extends from supply conductor L1 through conductor 120, the contact members of button 8U, conductor 121, restoring coil 122, conductor 123, contact segment 118, brush 14, conductors 130 and 132, the contact members d of relay 4, conductors 89, 94 and 95, the contact members 96, 62 and 63 of car switch CS and conductor 64 to supply conductor L2. The complete energization of the restoring coil 122 restores the push button 8U and extinguishes the signal lamp RL.

The centering of the car switch CS also completes a circuit for lighting the floor lantern L8U to indicate to the waiting passenger at the eighth floor that the car will stop at that floor, which circuit extends from supply conductor L1 through conductors 54 and 55, floor lantern L8U, conductor 133, contact segment 134, the high speed brush 10, conductor 135, the contact members h on high speed relay 4, conductors 94 and 95, the contact members 96, 62 and 63 on the car switch CS, and conductor 64 to supply conductor L2.

As the car continues toward the eighth floor stop, the arm MA moves along the floor selector until the intermediate speed brush 11 engages the contact segment 134 thereby causing the lighting of the floor lantern L8U to be transferred from brush 10 to brush 11 by way of a circuit that extends from supply conductor L1 through conductors 54 and 55, lamp L8U, conductor 133, segment 134, brush 11, conductor 102, the normally closed contact members g of the high speed relay 4, conductors 103 and 99, the contact members d on intermediate speed relay 3, conductor 95, the contact members 96, 62 and 63 of car switch CS and conductor 64 to supply conductor L2.

As the car comes to rest at the eighth floor landing, the arm MA on the floor selector moves to such position that the standing brush 12 is disposed on the contact segment 134 and, therefore, the circuit for lighting the floor lantern L8U is transferred from the intermediate speed brush 11 to the standing brush 12, which circuit now extends from supply conductor L1 through conductors 54 and 55, lamp L8U, conductor 133, contact segment 134, brush 12, conductor 105, contact members e of relay 3, conductor 95, the contact members 96, 62 and 63 the car switch CS and conductor 64 to supply conductor L2.

Thus the arrangement of the high speed brush 10, the intermediate speed brush 11 and the standing brush 12 causes the floor lantern L8U to be lighted when the car attendant centers the car switch CS to stop the car at the eighth floor and to thereafter remain lighted while the car slows down and while it stops at that floor. The floor lantern L8U will be extinguished when the car switch is moved to start the car by the separation of the contact members 62 and 96 on the car switch.

Assuming now that the car completes its stop at the eighth floor and that the attendant again moves the car switch CS in a clockwise direction, then the up direction switch 1 will be energized as previously described and the car will start up and move to the upper terminal floor.

As the car arrives at the end of its upward run and is brought to a stop by the usual terminal switches, the cam member 138 on the upper left-hand corner of the car C opens the limit switch 34 to deenergize the up-selector relay 32 and energize the down-selector relay 33 for causing the movable arm to be tilted over so that it bears upon the down-contact segments on the floor selector.

The circuit completed by the closing of the contact members a on the selector relay 32 for energizing the selector relay 33 extends from supply conductor L1 through conductor 141, the coil of relay 33, conductor 142, contact members a of relay 32, conductor 143, the contact members of down-limit switch 35 and conductor 144 to supply conductor L2.

The opening of the normally closed contact members a on the relay 33 prevents reenergization of the relay 32 until the relay 33 is again deenergized.

The closing of the contact members b on the relay 33 completes a circuit for energizing the electromagnet 31 to tilt the arm MA until it rests on the "down" contact segments, which circuit extends from supply conductor L1 through conductors 141 and 145, the contact members b of relay 33, conductor 146 the coil of magnet 31, and conductors 147 and 148 to supply conductor L2.

Assuming now that the car has taken on a number of passengers at the upper terminal and is ready to start down and that the car attendant moves the car switch CS in a counter-clockwise direction, then a circuit is completed for energizing the down-direction switch 2 to start the car downwardly which circuit extends from supply conductor L1 through conductors 54, 55, 56 and 57, the contact members of the inductor relay S, conductors 58 and 150, the coil of down direction switch 2, conductors 151 and 140, contact members 152, 62 and 153 of car switch CS and conductor 64 to supply conductor L2.

The closing of the contact members a on the down direction switch 2 completes a self-holding circuit for the down-direction switch 2 extending from supply conductor L1 to the coil of down-direction switch 2 as just described and thence through conductor 151, the contact members a of down-direction switch 2 and conductor 68 to supply conductor L2.

The closing of the contact members b and c on the down-direction switch 2 energizes the field winding GF of the generator G with current in the reverse direction by way of a circuit that extends from supply conductor L1 through conductors 70, 71 and 154, the contact members b of down-direction switch 2, conductor 73, field winding GF, conductors 72 and 155, the contact members c of down-direction switch 2, conductors 156 and 76, the resistor sections R1, R2 and R3 and conductor 77 to supply conductor L2.

The energization of the field winding GF causes the generator G to supply current in the reverse direction to the hoisting motor EM and the car starts downwardly.

As the attendant continues the movement of car switch CS in a counter-clockwise direction, a circuit is completed for energizing the intermediate speed relay 3 to cause the car to operate at its intermediate speed, which circuit extends from supply conductor L1 through conductors 54 and 89, the contact members of inductor relay SD, conductor 81, the contact members of inductor relay SU, conductor 82, the coil of relay 3 conductors 83, 84 and 151, contact members 158, 62 and 153 of car switch CS and conductor 64 to supply conductor L2.

The closing of the contact members a on the intermediate speed relay 3 completes a self-holding circuit for that relay which extends from supply conductor L1 to the coil of relay 3 as just described and thence through conductor 83, the contact members a of relay 3 and conductors 86 and 87 to supply conductor L2.

The closing of the contact members b on the intermediate speed relay 3 shunts the resistor section R3 from the circuit of the field winding GF, as previously described, thereby causing the car to travel at its intermediate speed.

Assuming that the attendant, desiring to cause the car to travel at a still greater speed, moves the car switch CS further in its counter-clockwise direction, then a circuit for energizing the high speed relay 4 to cause the car to travel at its high speed will be completed from supply conductor L1 through conductors 54, 80 and 107, the contact members of inductor relay HD, conductor 168, the contact members of inductor relay HU, conductor 109, the coil of relay 4, conductor 110, the contact members a of counter E. M. F. relay 7, conductors 111 and 159, the contact members 160, 62 and 153 of car switch CS and conductor 64 to supply conductor L2.

The closing of the contact members a on relay 4 completes a self-holding circuit for that relay extending from supply conductor L1 to the coil of the relay 4, as previously described, and thence through conductor 112, the contact members a of relay 4 and conductors 113, 86 and 87 to supply conductor L2.

The closing of the contact members b on the high speed relay 4 shunts the resistor section R2 from the circuit of the field winding GF, as previously described, thereby causing the car to travel at an increased speed.

Inasmuch as the "dispatcher" has not yet opened the express speed switch 9, the car is still conditioned to operate at express speed. Therefore, as soon as the generator reaches a predetermined speed, the counter E. M. F. relay 7 will close its contact members b to complete the hereinbefore described circuit for energizing the express speed relay 5. Consequently that relay 5 closes its contact members thereby shunting the resistor section R4 from the circuit of the field winding GF, as previously described, and causing the car to travel downwardly at express speed.

Assuming further that some of the passengers taken on at the upper terminal called out stops for the third and second floors and that the attendant pressed the push buttons C3 and C2 to register the stops indicated by the passengers, then a circuit has been partially prepared for lighting the signal lamps in the car to indicate to the car attendant when to center his car switch to make the stops at the third and second floors.

The pressing of the button C3 completed a self-holding circuit for that button extending from supply conductor L1 through conductors 54 and 161, the contact members of button C3, holding coil 162 and conductor 163 to supply conductor L2.

As the car approaches at express speed the down stop at the third floor, it will be decelerated from express speed to high speed because the arm MA on the floor selector will cause the express brush 21 to engage the energized contact segment 164 and thereby energize the express control relay 6 by way of a circuit which extends from the supply conductor L1 through conductors 54 and 161, the contact members of button C3, conductor 165, restoring coil 166, conductor 167, the contact segment 164, express brush 21, conductors 112 and 113, the coil 114 of relay 6, and conductors 125 and 77 to supply conductor L2.

The closing of the contact members b on the relay 6 completes a self-holding circuit for that relay as hereinbefore described.

The opening of the normally closed contact members a on the relay 6 deenergizes the express relay 5 and causes the car to decelerate from express speed to high speed as hereinbefore described.

As the car continues its approach to the down stop at the third floor, the high speed brush 20 engages the contact segment 164 on the floor selector and thereby completes the circuit partially prepared by the operation of the push button C3 for lighting the red signal lamp RL to indicate to the car attendant that a stop is to be made at the third floor, which circuit extends from supply conductor L1 through conductors 54 and 161, the contact members of button C3, conductor 165, restoring coil 166, conductor 167, the contact segment 164, brush 20, conductors 168 and 75

and 169, the filament *b* of lamp RL and conductor 170 to supply conductor L2.

As the lamp RL lights up to indicate the third floor stop, the car attendant centers the car switch 5 CS to energize the inductor relays HD, SD and S, as previously described, so that they will be actuated by the inductor plates HD', SD' and S' to bring the car to a stop at the third floor landing.

The centering of the car switch CS also completes a shunt circuit around the signal lamp RL and causes the restoring coil 166 to be fully energized so that it will overcome the holding coil 162 to release the push button C3 to its open position and completely extinguish the signal lamp 10 RL, which circuit extends from supply conductor L through conductors 54 and 161, the contact member of button C3, conductor 165, restoring coil 166, conductor 161, contact segment 164, brush 20, conductors 168, 169 and 170, the contact 15 members *f* of relay 4, conductors 89, 94 and 95, the contact members 96, 62 and 153 of car switch CS and conductor 64 to supply conductor L2.

The centering of the car switch CS for the 25 third floor stop also completes a circuit for lighting the floor lantern L3D at the third floor to indicate to passengers who may be waiting at that floor that the car is going to stop, which circuit extends from supply conductor L1, conductors 54 and 55, floor lantern L3D, conductor 172, contact 30 segment 173, brush 27, conductor 174, the contact members *j* of relay 4, conductors 175 and 176, contact members *f* of relay 3, conductor 95, the contact members 96, 62 and 153 of car switch CS and conductor 64 to supply conductor L2.

35 As the car continues toward the third floor, the floor selector arm MA moves downwardly until the low speed brush 26 engages the contact segment 173 and thereby causes the lighting of the floor lantern L3D to be transferred from brush 27 to brush 26 by way of a circuit that extends from the supply conductor L1 to the contact segment 173 as previously described and then through brush 26, conductor 177, the contact members *i* of relay 4, conductor 176, the contact members *f* of relay 3, conductor 95, contact members 96, 62 and 153 of the car switch CS and conductor 64 to supply conductor L2.

As the car comes to rest at the third floor landing, the arm MA on the floor selector moves 50 to such position that the standing brush 25 is disposed on the contact segment 173 thus transferring the circuit for lighting the floor lantern L3D from the low speed brush 26 to the standing brush 25, which circuit now extends from the supply conductor L1 to the contact segment 173 as previously described, and then through brush 25, conductor 178, the contact members *c* of relay 3, conductor 95, the contact members 96, 62 and 153 of car switch CS and conductor 64 to supply conductor L2.

60 Thus the arrangement of the high-speed brush 27, the intermediate speed brush 26 and the standing brush 25 causes the floor lantern L3D to be lighted when the car prepares to stop at the third floor and to thereafter remain lighted while the car slows down and while it stops at that floor.

Assuming now that the stop at the third floor 70 is completed and recalling that the car attendant pressed the car button C2 to indicate a stop at the second floor, then the pressing of the button C2 completed a self-holding circuit for that button, extending from supply conductor L1 through conductors 54 and 161, the contact mem-

bers of button C2, holding coil 180 and conductor 163 to supply conductor L2.

Inasmuch as the button C2 has been pressed for a down stop at the second floor, the standing of the car at the third floor will cause a circuit to be completed for lighting the signal lamp GL in the car to indicate to the car attendant that he should operate the car for a one-floor run to the next floor below, which circuit extends from the supply conductor L1 through conductors 54 and 161, the contact members of button C2, conductor 181, restoring coil 182, conductor 183, contact segment 184, standing brush 19, conductors 185, 186 and 187, the contact members *e* of up direction switch 1, conductor 188, contact members *e* of down direction switch 2, conductor 189, filament *b* of lamp GL and conductor 190 to supply conductor L2.

Upon receiving the signal by the lighting of the lamp GL for a stop at the next floor below, the car attendant moves the car switch in the counter-clockwise direction to engage the contact member 159 thereon for operating the car for a one-floor run. Thereupon the car will start down and accelerate to its intermediate speed as previously described. As soon as the car gets under way, the car attendant centers the car switch CS for the down stop at the second floor, thus energizing the inductor relay as previously described and bringing the car to a stop at the second floor. As previously described, the car attendant may, in practice by reason of the counter E. M. F. relay 1, throw the car switch all the way over momentarily and then immediately re-center it, for the one-floor run.

35 Inasmuch as the car is moving and the intermediate speed relay 3 is energized at the time the car switch is centered, a circuit will be completed for fully energizing the restoring coil 182 to overcome the holding coil 180 and thus restore the button C2 to its open position, which circuit extends from supply conductor L1 through conductors 54 and 161, the contact members of button C2, conductor 181, restoring coil 182, conductor 183, contact segment 184, brush 19, conductors 185 and 186, the contact members *e* of relay 4, conductors 191, 193 and 99, the contact members *d* of relay 3, conductor 95, the contact members 96, 62 and 153 of car switch CS and conductor 64 to supply conductor L2.

The centering of the car switch will also complete the circuits for lighting the floor lantern L2D in the manner previously described. After the down stop at the second floor is completed the car may be operated to answer such further calls as may exist.

Thus it will be seen that I have provided a signal system for use in connection with elevators that serves to indicate the registered condition of the buttons, that provides for restoring the button as soon as the car is conditioned to answer the call set up by the buttons, and which requires a relatively small number of parts and a minimum amount of wiring.

While I have illustrated and described only one specific embodiment of my invention, I realize it is susceptible of many modifications. Therefore, I do not desire to be limited to the precise construction illustrated and described except as defined in the appended claims.

I claim as my invention:

1. In an elevator system having a car, means for operating the car at a normal high speed, separate means for causing the car to operate at an express speed above its normal high speed,

means for registering calls for stops to be made by the car, means responsive to the registration of a stop call and to the approach of the car to that call for causing the car to "pick up" 5 the said call at a point a predetermined distance from the floor corresponding thereto, and means responsive to the registration of said call and to the approach of the car to said point for rendering said separate express speed means ineffective 10 whereby the car may "pick up" the said call while operating at normal speed.

2. In an elevator system having a car, means for operating the car at a normal high speed, 15 separate means for causing the car to operate at an express speed above its normal high speed, means for registering calls for stops to be made by the car, means responsive to the registration of a stop call and to the approach of the car to that call for causing the car to "pick up" the 20 said call at a point a predetermined distance from the floor corresponding thereto, control means responsive to the registration of said stop call and to the approach of the car to said point for rendering said express speed means ineffective 25 whereby the car may "pick up" said stop call while operating at normal speed, means responsive to the operation of the control means effective to maintain the same in operated condition, a control system for stopping the car, and means 30 responsive to the operation of the said control system for rendering the maintaining means ineffective.

3. In a signal system for an elevator car operable at a normal high speed and at an express 35 speed past a landing floor, means operable at a dispatching station for causing the car to operate at express speed, means for registering a call for the car to stop at the floor, means operably responsive to the approach of the car to the floor 40 for causing the car to receive the registered call for a stop at a distance from the floor which will permit deceleration of the car from its normal high speed to a stop level with the floor after receiving the registered call, and means operably 45 responsive to the position of the car and to the registration of the call for decelerating the car from its express speed to its normal high speed prior to its receipt of the registered call.

4. In an elevator system having a car, operable 50 at a normal high speed, means operable at a dispatching station for causing the car to operate at an express speed above its normal high speed, means for registering calls for stops to be made by the car, and means responsive to the regis-

tration of a call for a stop and to the approach of the car to said stop for rendering the express speed means ineffective.

5. In an elevator system having a car operable at a normal high speed, means operable at a dispatching station for causing the car to operate at an express speed above its normal high speed, 5 means for registering calls for stops to be made by the car, means responsive to the registration of a call for a stop and to the approach of the car to said stop rendering the express speed means ineffective, a control system for decelerating and stopping the car from its normal high speed, and means responsive to operation of the said ineffective-rendering means and to the said control system for maintaining the ineffective-rendering means in operated condition until the control system operates to stop the car.

6. In an elevator system having a car operable at a normal high speed, means operable at a dispatching station for causing the car to operate at an express speed above its normal high speed, 10 means for registering calls for stops to be made by the car, a relay, means responsive to the registration of a call for a stop and to the approach of the car to said stop for energizing said relay to render the express speed means ineffective, a control system for decelerating and stopping the car from its normal high speed, and means responsive to energization of the relay and 15 to the said control system for maintaining the relay energized until the control system operates to stop the car.

7. In an elevator system having a car operable at a normal high speed, means on the car for 20 causing it to operate at its normal high speed, means operable at a dispatching station for causing the car to operate at an express speed above its normal high speed, and means responsive to operation of the car at less than its normal high speed for rendering the express speed means ineffective until the car attains its normal high speed.

8. In an elevator system having a car, a motor for operating the car at a normal high speed and 25 at an express speed above its normal high speed, means operable at a dispatching station for causing the motor to operate the car at express speed, and means responsive to the terminal voltage applied to said motor for rendering the express 30 speed means ineffective until the terminal voltage reaches a predetermined value.

WILLIAM F. EAMES.
